ELECTRICAL HEATER

Charles J. Young, Princeton, N.J., assignor to Radio Corporation of America, a corporation of Delaware

Filed June 22, 1962, Ser. No. 204,441

3 Claims. (Cl. 219—550)

This invention relates generally to improved electrical heating elements and particularly to improved resistive electrical heating elements of the type employing a ribbon of resistive material.

In heat exchange systems wherein a flow of air is to be rapidly heated, a ribbon type of resistive electrical heater element is preferred since it provides more surface than a wire of the same cross-section, and therefore more efficient heat exchange. However, such a ribbon element is mechanically unstable because of thermal expansion and loss of stiffness at red heat. This is particularly true wherein the element must be a relatively thin ribbon in order to satisfy fixed requirements of wattage and supply voltage. Ordinarily, a looped or folded thin ribbon of resistive material loosely supported in channels of insulating material becomes distorted when heated, causing uneven distribution of heat.

An object of the present invention is to provide an improved electrical heating element.

Another object is to provide a resistive heating element having improved mechanical stability.

A further object is to provide a resistive heating element having improved uniformity of heat emission.

Another object is to provide an electrically resistive heating element providing improved and efficient heat exchange.

The foregoing objects and advantages are provided in accordance with the invention which comprises a resistive ribbon type electric heating element including a plurality of convolutions of the ribbon element wherein each convolution mechanically contacts the next adjacent convolutions at a plurality of evenly-spaced points intermediate the ends of the convolutions thereby providing improved mechanical support and stability.

The several convolutions in contact with the adjacent convolutions may provide diamond-shaped, cusp-shaped or triangular-shaped, or the like, openings therebetween for the passage of air to be heated. Insulation between the contacting portions of the adjacent convolutions may be provided by surface oxidation of the heating element or by interposed insulating strips. The heating elements may comprise single or multiple pancakes of such convolutions, connected in series or parallel, and with the convolutions arranged either longitudinally, or annularly. The successive convolutions of each resistive element may be supported loosely in channels of cooperating parallel or concentric insulating supports.

The invention will be described in greater detail by reference to the accompanying drawings in which:

FIG. 1 is an end view of a resistive element with its cooperating channels in insulating supports;

FIG. 2 is a schematic side view representation of a prior art ribbon type heating element;

FIG. 3 is a schematic side view representation of a first embodiment of the invention showing diamond-shaped openings between adjacent heating convolutions;

FIG. 4 is a schematic side view representation of an expanded portion of the heater element of FIG. 3;

FIG. 5 is a schematic side view representation of a modification of the convolution arrangement of FIG. 3 showing a heating element having a larger number of diamond-shaped openings between adjacent convolutions;

2

FIG. 6 is a schematic side view representation of another embodiment of the invention showing convolutions having a plurality of cusp-shaped portions contacting similar portions in adjacent convolutions;

5 FIG. 7 is a schematic side view representation of a third embodiment of the invention showing a plurality of zig-zag convolutions interspersed between straight ribbon portions of the heating element;

10 FIG. 8 is similar to FIG. 5 with the exception that adjacent convolutions are insulated one from the other by mica or other insulating sheets, indicated by dash lines, loosely supported between said convolutions;

15 FIG. 9a is a schematic end view representation of a fourth embodiment of the invention showing an annular arrangement of the resistive element of FIG. 3;

FIG. 9b is a modification of the embodiment shown in FIG. 9a with the type of resistive element shown in FIG. 5; and

20 FIG. 10 is a schematic cross-sectional view taken along the section line 10—10 of FIGS. 9a and 9b of a plurality of annular resistive elements in a blower structure.

Similar reference characters are applied to similar elements throughout the drawings.

25 Referring to FIGS. 1 and 2 of the drawing, a prior art resistive type electric heater element 1 includes successive loops of Nichrome ribbon loosely supported in channels 3, 5 of insulating supports 7, 9, respectively. The insulating supports may comprise any insulating

30 ceramic material capable of withstanding the heat generated by the element 1. As shown by the dash lines 11, when the heating element 1 is heated to a bright red temperature, the successive convolutions become distorted, thereby providing haphazard electrical contact 35 therebetween and uneven heat distribution along the length of the element 1. Furthermore, the rounded portions 13 within the channels 3, 5 have a substantial area which is out of the circulation path of air blown through the heating element as indicated by the arrow 40 15 in FIG. 1.

FIG. 3 shows an embodiment of the invention wherein the heating element 1 comprises a metal ribbon of resistive material such, for example, as Nichrome which is preformed to provide a diamond-shaped pattern of openings between successive convolutions of the heating element. The ends 17 of the convolutions form angles which are loosely supported within the channels 3, 5 in the ceramic insulating supports 7, 9, respectively. The angles 17 at the ends of the successive convolutions provide a minimum area of the element 1 outside of the direct air flow through the heating element. The diamond-shaped convolutions are uniformly arranged to provide an even number of contacting points 19 between adjacent convolutions. The ends of the heating element are terminated in any desired manner in suitable terminals 21. The desired number of convolutions of the heating elements are squeezed together in firm contact with each next adjacent convolution by ceramic plugs 23.

50 Prior to the final assembly, the successive convolutions are stretched apart as shown at the right in FIG. 4 and heated to a bright red temperature to form an oxidized coating thereon which will prevent electrical contact between successive convolutions at the points 19 when the heating element is finally compressed as shown in FIG. 3. If desired, an oxidizing atmosphere will assist in forming the oxidized layer on the heating element. If on assembly one or more bright spots are found at contacting points 19, the oxidation process is repeated until this condition is overcome.

55 A heater element as shown in FIG. 3, having a cross-sectional area of only 1 x 9 inches, has been tested for

hundreds of hours of operation with substantially no deformation of the convolutions thereof and no shorting of the contacting points 19 while dissipating power of the order of 1200 watts. Since substantially no deformation occurs, uniform heat distribution throughout the length of the heater element is provided.

FIG. 5 shows a heater element similar to that shown in FIG. 3, but having four contacting points 19 between one convolution and the adjacent convolutions of the heater on either side of the one to provide desired structural stability for heater elements of greater width or thinner ribbon than provided in the structure of FIG. 3. The diamond-shaped openings provided by the zig-zag convolutions of the heater elements of FIGS. 3 and 5 can be extended to any desired width, but the intersecting points between one convolution and the two adjacent convolutions will always be even in number.

FIG. 6 shows another embodiment of a ribbon heater element in accordance with the invention wherein instead of preformed zig-zag convolutions, each convolution includes a number of arcuate or cusp-shaped portions each contacting the center of similar arcs or cusps at the points 20, and wherein, as in FIGS. 3 and 5, there are an even number of such contacting points between adjacent convolutions.

FIG. 7 shows another embodiment of the zig-zag convolutions having a straight convolution 21 interspersed between alternate zig-zag convolutions 23. This arrangement also provides an even number of contacting points 25 between adjacent convolutions. However, the structure of FIG. 7 does not provide as great mechanical stability as the structures of FIGS. 3, 5 and 6 although the heat transfer characteristics thereof are quite similar.

While in FIGS. 3, 5, 6 and 7 insulation of the surface of the resistive element is provided by oxidation thereof to prevent electrical contact at the successive mechanically-contacting points between successive convolutions, FIG. 8 shows an alternative arrangement, having convolutions shaped similar to FIG. 5, but wherein the insulation between successive convolutions is provided by thin mica, or other insulating, sheets indicated by the dash lines 27. The insulating sheets 27 may be loosely supported between adjacent convolutions merely by the pressure exerted thereon to squeeze them together in the final assembly of the heater element.

FIG. 9a shows an annular type of diamond-shaped heater element wherein the zig-zag convolutions are supported in concentric channels 31, 33 in concentrically disposed ceramic cylinders 35, 37, respectively. The ends of the heater element 29 are terminated in suitable terminals 39, 41 and are physically separated by a radial ceramic insulator 43.

The structure of FIG. 9b is similar to that of FIG. 9a with the exception that each successive convolution includes a larger number of contacting points 19, as in the structure of FIG. 5. It should be understood that the shape of the convolutions may alternatively be according to the teachings of FIGS. 6 or 7 or the like, and that if desired the insulating spacers 27 of FIG. 8 may be substituted for the oxidized surface on the heater element to prevent electrical contact between successive convolutions.

FIG. 10 shows an arrangement wherein a plurality of annular heaters 51, 53 as in FIGS. 9a or 9b are arranged in parallel pancakes, supported in concentric slots 55, 57 of ceramic supports 59, 61, respectively. The heater elements 51, 53 may be electrically connected in series or in shunt as desired. An air stream indicated by the arrows 63 is provided by a blower fan 65 driven by a motor 67

which supports the center ceramic support 59. The motor is supported within the outer ceramic support by radial legs 69. It will be seen that the fan 65 cools the motor 67 prior to projecting the air stream 63 through the successive heaters 53, 51.

What is claimed is:

1. An electrical heating element comprising a single continuous ribbon of electrically resistive material formed into a pattern of a plurality of successive complementary convolutions, the ends of each convolution forming an angle with the next adjacent convolution, cooperating insulating supports for said ends channeled to receive said ends in slideable contact, alternate ones of said convolutions having a zig-zag conformation to contact a next adjacent substantially straight convolution at regularly-spaced points intermediate said ends thereof to increase the rigidity of said ribbon element, means for insulating said ribbon element at said contact points, and means for connecting said ribbon to a source of electrical energy.

2. An electrical heating element comprising a single continuous ribbon of electrically resistive material formed into a pattern of a plurality of successive complementary convolutions, the ends of each convolution forming an angle with the next adjacent convolution, cooperating insulating supports for said ends being channeled to receive said ends in slideable contact, each of said convolutions having a zig-zag conformation to contact the next adjacent convolutions at an even number of regularly-spaced points intermediate said ends thereof to increase the rigidity of said ribbon element, means comprising an oxide layer on the surface of said material for insulating said ribbon element at said contact points, and means for connecting said ribbon to a source of electrical energy.

3. An electrical heating element comprising a single continuous ribbon of electrically resistive material formed into a pattern of a plurality of successive complementary convolutions, the ends of each convolution forming an angle with the next adjacent convolution, insulating supports for said ends being channeled to receive said ends in slideable contact, each of said convolutions having a zig-zag conformation to contact the next adjacent convolutions at a number of regularly-spaced points intermediate said ends thereof to increase the rigidity of said ribbon element, means comprising an oxide layer on the surface of said material for insulating said ribbon element at said contact points, and means for connecting said ribbon to a source of electrical energy.
